Specification for Design.

Patented Mar. 29, 1921.

Application filed February 25, 1920. Serial No. 361,263. Term of patent 14 years.

To all whom it may concern:

Be it known that I, VICTOR LOEWENBERG, a citizen of the United States, residing in the borough of Manhattan, city, county, and State of New York, have invented a new, original, and ornamental Design for a Bedpan, of which the following is a specification, reference being had to the accompanying drawing, forming part thereof.

In the drawings, Figure 1 is a perspective view showing the form of my bed pan and cover separated;

Fig. 2 is a perspective view showing the bed pan and cover together; and

Fig. 3 is a longitudinal section substantially on the line 3—3 of Fig. 2 showing the details of shape and outline.

I claim:

The ornamental design for a bed pan, as shown.

VICTOR LOEWENBERG.
